UNITED STATES PATENT OFFICE.

JAMES ARTHUR PETERS, OF THE WHITE HOUSE, NEAR SCARBOROUGH, ENGLAND.

SPRING FORK FOR MOTOR CYCLES.

1,413,352.

Specification of Letters Patent. Patented Apr. 18, 1922.

Application filed January 12, 1922. Serial No. 528,683.

To all whom it may concern:

Be it known that I, JAMES ARTHUR PETERS, a British subject, residing at The White House, near Scarborough, in the county of Yorkshire, England, have invented certain new and useful Improvements in Spring Forks for Motor Cycles, (for which I have filed an application in England October 21, 1920, No. 29,830,) of which the following is a specification.

This invention relates to an improved springing mechanism for the wheels of motor cycles, light cars and the like, and is primarily designed for use in connection with a construction of motor cycle of the kind described in my co-pending application No. 528682 wherein the rear wheel of a motor cycle is held at the end of a radius-rod which at its forward end is hinged to the frame. The arrangement is, however, capable of application generally to automobiles.

According to the invention, the springing is effected by means of the interposition between telescopic members of two springs, one of which is the load-supporting spring and is normally in compression and the second is normally under slight tension and only comes into effective operation to damp recoil due to the action of the first-mentioned spring, or after a certain amount of lost motion to form a supplementary buffer to resist extreme compression of the first-mentioned spring in case of excessive load or shock. The invention further comprises lubricating means for the said fork in certain forms.

One form of carrying the invention into effect is illustrated in the accompanying drawing in which Fig. 1 illustrates the general arrangement of a spring fork as applied to a motor cycle, and Fig. 2 a sectional view of the spring mechanism.

Referring now to the drawing, the spring fork comprises the forked arms *a* rigidly mounted on a cylindrical extension *b* in which is adapted to slide an open-ended plunger *c*. The ends of the forked arms *a* and of the plunger *c* are bored as shown at *d* for pivotal attachment to the frame. Within the telescopic parts *b*, *c* is fitted a spiral compression spring *e* adapted to support the plunger-head against load, and within the said spring *e* is fitted a spiral tension spring *f* which is secured to the

fork and plunger by means of bolts *g*, *h*. The lower end of the spring *f* is slidable upon the bolt *h* and under normal load occupies the position shown in the drawing and is under slight tension.

In the case of excessive load or shock, the depression of the plunger-head is first taken up by the spring *e* and then also by the spring *f* after the plunger-head has moved a distance approximately equal to the height of the bolt *h*. Thus the second spring *f* acts as a buffer to resist extreme compression of the primary supporting spring *e*. On recoil, excessive movement of the plunger-head beyond its normal position is resisted by the tension spring *f* which is stronger than the compression spring; and vibration of the plunger-head is effectually damped out.

In the form shown, the fork is filled with lubricant and the movement of the plunger-head during use is adapted to lubricate the upper bearing *d* by the provision of a central tube *j* rising upwardly to the said upper bearing and communicating therewith through an opening *m*, through which oil is forced from time to time on the depression of the plunger-head. Borings *h* at the lower end of the forks give access to the lower bearings *d*, which are also maintained lubricated. The extension *b* is fitted at its upper end with a felt washer *l* to keep the joint clean.

Whilst illustrated as employed in a hinged oblique support for a motor cycle rear wheel, the springing system is not limited to this application but may be applied vertically to the axles of light cars or other automobiles where found suitable.

I claim:

1. In a motor cycle, means for springing a road wheel comprising a frame, telescopic means secured to said frame for holding said wheel the upper end of said means being hinged to said frame, a load-supporting spiral compression spring within said telescopic means, one end of said spring being anchored to one element of said means, a supplementary spring concentric with and of greater strength than said compression spring and having one end in fixed relation to said anchored end of said compression spring, a pair of oppositely placed abutments positioned in fixed relation to the second element of the telescopic means, the

free end of the second spring being capable of limited movement between the two abutments and the relative strength of the springs being such that one abutment only 5 comes into operation on excessive load and the other abutment on excessive recoil of the compression spring.

2. In a motor cycle, means for springing a road wheel comprising a telescopic pillar 10 terminating in a wheel fork, a load supporting spiral compression spring within said pillar, a supplementary spiral spring concentric with and of greater strength than said compression spring, the said springs 15 being relatively so adjusted that the supplementary spring serves on excessive load as a compression spring and on excessive recoil of the load-supporting spring as a tension spring, and means for allowing a 20 certain amount of lost motion between the two operative ranges of the supplementary spring.

3. In a vehicle, means for springing a road wheel comprising a hollow telescopic pillar 25 terminating at its lower end in a hollow

wheel fork, a transverse pivot bearing at the upper end of said pillar, wheel axle bearings at the lower ends of said fork, load-supporting spring mechanism seated within said pillar, means for storing and retaining lubricant within said pillar and fork, and means for causing lubricant to be supplied therefrom to said bearings during use. 30

4. In a vehicle, means for springing a road wheel comprising a hollow telescopic pillar terminating at its lower end in a hollow wheel fork, a transverse pivot bearing at the upper end of said pillar, wheel axle bearings at the lower ends of said fork, load-supporting spring mechanism seated 35 within said pillar, means for storing and retaining lubricant within said pillar and fork, and means for causing lubricant to be supplied therefrom to said bearings during use, comprising perforations in the walls 40 of said bearings, and a tube depending from the perforation in the wall of the upper bearing. 45

In testimony whereof I affix my signature.
JAMES ARTHUR PETERS.
